RUG CLEANING MACHINE

Sheldon David Hulsh, 530 Park Ave., New York, N.Y.

Filed Dec. 16, 1959, Ser. No. 58,684

Term of patent 14 years

(Cl. D9—2)

The handle is fragmentarily shown in Figures 2 to 5 for convenience of illustration only.

I claim:

The ornamental design for a rug cleaning machine, substantially as shown and described.
